US00D599655S

(12) **United States Design Patent**
Friebe et al.

(10) **Patent No.:** **US D599,655 S**
(45) **Date of Patent:** **** Sep. 8, 2009**

(54) **FOIL PACKAGE**

(75) Inventors: **Joachim Friebe**, Heimertingen (DE);
Andreas Michalsky, Memmingen (DE);
Maurice Habram, Kempten (DE);
Agata Surdziel, Kempten (DE); **Peter Ganz**, Untrasried (DE)

(73) Assignee: **Huhtamaki Ronsberg,
Zweigniederlassung der Huhtamaki
Deutschland GmbH & Co. KG (DE)**

(**) Term: **14 Years**

(21) Appl. No.: **29/299,491**

(22) Filed: **Dec. 27, 2007**

(57) **CLAIM**

The ornamental design for a foil package, as shown and described.

DESCRIPTION

FIG. 1 is a first front side perspective view of a foil package and movable cover showing our new design with the cover in an open position;

FIG. 2 is a second front side perspective view thereof with a removable lid on the foil package and the cover in an open position;

FIG. 3 is a third front side perspective view thereof with the cover in a closed position;

FIG. 4 is a bottom view thereof with the cover in the closed position;

FIG. 5 is a front view thereof with the cover in the closed position;

FIG. 6 is a front perspective view thereof with the cover in the closed position;

FIG. 7 is a top view thereof with the cover in the closed position; and,

FIG. 8 is a perspective view thereof with the cover in the closed position.

The broken lines shown in the drawings are for illustrative purposes only and form no part of the claimed design.

1 Claim, 3 Drawing Sheets
